UNITED STATES PATENT OFFICE.

ALEXANDER CRUICKSHANKS, OF RICHMOND, VIRGINIA.

PUNCHING-MACHINE.

SPECIFICATION forming part of Letters Patent No. 655,327, dated August 7, 1900.

Application filed September 28, 1899, Serial No. 731,919. (No model.)

To all whom it may concern:

Be it known that I, ALEXANDER CRUICKSHANKS, a citizen of the United States of America, and a resident of Richmond city, State of Virginia, have invented certain new and useful Improvements in Punching-Machines, of which the following is a specification.

My invention relates to punches, and particularly to the class known as "portable hand-punches," which may be economically employed in the punching of thin sheet and of the softer metals; and it consists of a punch-arm and a die-arm carrying, respectively, a punch and a die at one end and pivotally connected at the other end and having means situated between the punching ends and the pivotally-connected ends whereby the said arms may be given the motion necessary for the operation of punching.

My invention can be used not only as a portable punch, but also as a stationary punch by fixing it in a vise or by attaching it to a post, wall, or other fixed object. This is made possible and convenient by the placing of the operating mechanism, which preferably consists of a pin having eccentric or cam parts, which parts engage in the arms of the punch between the pivotally-connected ends and the punching ends of the arm. Another great advantage of this location of the operating mechanism is the obtaining in a given length of punch-arm as great a distance as possible between the pivoted and punching ends of the arms, thus making the arc described by the punch when in operation more nearly approach a straight line and so rendering the operation of punching easier and cleaner and also lengthening the life of the punch and die.

My invention possesses other advantageous features, which will be referred to hereinafter.

In the drawings, which accompany and form a part of this specification, Figure I is a side elevation of the portable punch. Fig. II is a plan of the same. Fig. III is a detail showing the eccentric-pin. Fig. IV is an end view of the eccentric-pin with the nut and collars omitted for the sake of clearness. Fig. V is another view of the eccentric-pin, showing a slightly-modified construction. Figs. VI and VII are respectively the plan

and elevation of the bushing. Figs. VIII and IX show the punching ends or heads of the punch-arm and the die-arm, respectively. Fig. X is a broken view in elevation of the punch-arm head, showing an alternative method of securing the punch.

In Fig. I, 1 and 2 are the arms which carry the punch and die and which are pivotally connected by means of the bolt 3. One of the arms, preferably the die-supporting arm 2, extends beyond the pivot 3, as shown at 4. This extension 4 serves a double purpose. When using the punch as a portable punch, the operator's helper can by slipping a piece of pipe over the extension form a longer arm or handle wherewith to support the punch. In using the punch as a stationary punch the extension 4 can be clamped between the jaws 70 of the vise, or it can be bolted to any suitable fixed object or to a knee or bracket, which may in turn be bolted to the fixed object. Thus it will be seen that the punch can be used in practically any desired position. 75 Holes 22 22 are provided in the extension 4 for bolts.

Located in the cheeks of the arms—that is, between the punching ends and the pivotally-connected ends of the arms—is the operating mechanism, which consists of a pin having an eccentric portion and which on being rotated will cause the punch and die heads of the arms 1 and 2 to approach and recede from one another. This pin is shown in detail in Fig. III, referring to which the line x y is the principal axis of the pin. 20 is a square head. 19 is a collar, preferably forged solid on the pin. 18 is a cylindrical part having or not having, as will be hereinafter explained, 80 its axis coincident with the principal axis x y of the pin. 17 is another cylindrical part, whose axis is not coincident with the axis of the part 18 and which, with the part 18, consequently forms an eccentric. 14 is a loose collar. 13 is a nut which engages a threaded part 26 of the pin and which on being tightened up causes the loose collar 14 to bear against the shoulder 23. The threaded part 26 is preferably made concentric with the part 17, as thereby a greater diameter is obtainable than if it were made concentric with the principal axis x y . The pin terminates with another square head 12; but this head

may be omitted, if desired. The distance between the two collars 14 and 19 when the former is brought up to the shoulder 23 is very slightly in excess of the combined thickness 5 of the cheeks of the arms 1 and 2, the excess being allowed so that the collars shall not while holding the pin and the arms firmly in position cause the said arms to bind upon one another.

- 10 In the arm 2 is an aperture 24, which neatly engages the cylindrical part 18 of the pin, the length of the said aperture and of the part 18 being the same. In the arm 1 is a rectangular aperture 15, in which is neatly fitted the bushing 16. In this bushing is an aperture 25, adapted to neatly engage the part 17 of the pin. The rectangular aperture 15 is sufficiently longer in a direction at right angles to the line of motion of the punch than the 15 bushing 16 to allow for the motion in the said direction imparted to the latter by means of the part 17 when the pin is rotated.

As hereinbefore stated, the part 18 of the pin may have its axis coincident or not with 25 the principal axis $x-y$ —that is, with the axis of the square head 20.

In some cases it may be found to be desirable to have the part 18 also engage in a bushing fitted in the arm 2, as shown by dotted lines at 27 30 in Fig. IX, instead of merely in a circular aperture cut in the said arm. In such cases it is perhaps better to construct the pin as shown in Fig. V, in which the principal axis of the pin—that is, the center of the square head 20—falls 35 between the axes of the eccentric parts 18 and 17. This construction will be found desirable where a larger throw of the punch is necessary, as by dividing the horizontal motion of the bushings between the said bushings and 40 so by admitting of shorter rectangular apertures in which to fit the bushings it will render unnecessary any material increase in the depth, and consequently in the weight of the “cheeks” of the arms, which additional depth 45 and weight would be necessary were the whole throw of the eccentric-pin to be communicated to one bushing only.

The eccentric-pin is operated by means of a wrench or lever 21, one end of which is provided with a socket adapted to engage the square head 20 of the pin.

8 is a punch having a threaded portion 9 engaging in an aperture in the head of the arm 1. The aperture may be threaded to engage the threads on the punch-body, in which ease the punch is securely locked in place by means of a nut 11; but it may be sometimes found desirable to fix the punch as shown in Fig. X, wherein the aperture in the head of 55 60 the arm is not threaded, but is made of just sufficient diameter to admit of the punch-body being passed through it. The punch is then secured by means of two nuts 11 and 11^a. Whichever method of fixing the punch 65 is employed, it will be seen that the distance the punch projects through the head of the arm can be quickly adjusted. The upper end

of the punch is provided with means for turning the latter, such as a square head or a screw-driver slot, as shown at 10.

The head of the arm 2 is bored, as shown at 7, the upper end of the bore being increased in diameter to receive the die 5, which may be given additional security by means of a set-screw 6. The perforation of the die is 75 concentric with the bore 7, the latter being sufficiently large to provide a means of escape for the burs.

The above-described methods of fixing the punch in the arm have great advantages. 80 Any slackness due to wear may be immediately taken up by means of the nut or nuts, the punch will never get out of line with the die during its useful life, the gap between the punch and the die, and consequently the 85 necessary throw of the lever 21, can be adjusted rapidly and certainly for different thicknesses of metal, and should it be necessary to remove the punch or die the same can be done without taking the arms apart. 90 To effect the removal of the punch when secured as shown in Fig. I, the nut 11 is slackened, when the punch can be easily withdrawn by means of a screw-driver. When it is secured as shown in Fig. X, the nut 11^a 95 is slackened and run off. The punch can then be quickly withdrawn by hand. To remove the die, the punch is run upward until it is within the head of the arm, whereupon the die can be taken out.

Having described my invention, what I claim, and desire to protect by United States Letters Patent, is—

1. In a hand-punch, the combination of a punch, a die, a punch-arm, a die-arm, the 105 said arms being pivotally connected at one end, and carrying, respectively, the punch and the die at the other end, a rotatable eccentric-pin located between the pivotally-connected ends and the punch and die carrying 110 ends of the arms, and adapted to give, when rotated, to the arms a reciprocating motion, and means for rotating the eccentric-pin.

2. In a hand-punch, the combination of a punch, a die, a punch-arm, a die-arm, the 115 said arms being pivotally connected at one end, and carrying, respectively, the punch and the die at the other end, and one of the arms being extended beyond the pivot, a rotatable eccentric-pin located between the 120 pivotally-connected ends and the punch and die carrying ends of the arms, and adapted to give, when rotated, to the arms a reciprocating motion, and means for rotating the eccentric-pin.

3. In a hand-punch, the combination of a punch, a die, a punch-arm, a die-arm, the said arms being pivotally connected at one end, and carrying, respectively, the punch and the die at the other end, and one of the arms being extended beyond the pivot, a rotatable eccentric-pin located between the pivotally-connected ends and the punch and die carrying 130 ends of the arms, and having a part adapt-

- ed to engage in a perforation in one of the arms, and having another part which is eccentric with the first-mentioned part, and which is adapted to engage in a slidable bushing in the other arm, and having collars adapted to keep the punch and die arms and the eccentric parts of the pin in proper relative position, and means for rotating the eccentric-pin. 5
- 10 4. In a hand-punch, the combination of a punch, a die, a punch-arm, a die-arm, the said arms being pivotally connected at one end, and carrying, respectively, the punch and the die at the other end, and one of the arms being extended beyond the pivot, a rotatable eccentric-pin located between the pivotally-connected ends and the punch and die carrying ends of the arms, and having eccentric parts adapted to engage in slidable bushings 15 in the arms, and having collars adapted to keep the punch and die arms and the eccentric parts of the pin in proper relative position, means for rotating the eccentric-pin, and bushings slidably fitted one in each arm, and 20 adapted to engage the eccentric parts of the pin. 25
5. In a punching-machine, a die-arm, a punch-arm, the said arms being pivotally con-
- necting at one end, and carrying, respectively, the die and the punch at the other end, and one of the said arms being extended beyond the pivot, a die, an adjustable punch adapted to engage in a perforation in the punch-arm, and adapted to be secured in position by means of a nut or nuts engaging threaded portions of its body, in combination with a rotatable eccentric-pin located between the pivotally-connected ends and the punch and die carrying ends of the arms, and adapted and arranged to give, when rotated, to the said arms a reciprocating motion, and means for rotating the eccentric-pin. 30
- 35 6. In a punching-machine the combination, of two punching-jaws pivoted together at their rear ends and connected near their forward ends by a pin journaled in the arms, one portion of the said pin in one of the arms being eccentric with reference to the other portion, and means for rotating the pin substantially as described. 40
- 45 Signed by me at Richmond, Virginia, this 31st day of August, 1899.
